OWL WHISTLE

John H. Bacon, Wellesley Hills, and Stuart J. Bowen,
Fitchburg, Mass.

Application January 24, 1956, Serial No. 39,893

Term of patent 14 years

(Cl. D34—15)

FIG. 1

FIG. 2

FIG. 3

Figure 1 is a front plan view of an owl whistle, showing our new design;

Figure 2 is a side plan view thereof; and

Figure 3 is a rear plan view thereof.

We claim:

The ornamental design for an owl whistle, as shown.
